MACHINE FOR FLANGING CAN BODIES HAVING SOLDERLESS SIDE SEAMS

Paul E. Pearson, Chicago, Ill., assignor to Continental Can Company, Inc., New York, N. Y., a corporation of New York

Application December 27, 1940, Serial No. 371,975

16 Claims. (Cl. 153--21)

The invention relates generally to the manufacture of metallic containers having solderless side seams, or more particularly to containers having solderless side seams including paper strip inserts applied as by mechanisms disclosed in co-pending application for U. S. Letters Patent Serial Number 371,974, filed by Paul E. Pearson on December 27, 1940, and it primarily seeks to provide a novel machine for flanging the ends of container bodies including such side seams.

It has been proposed, heretofore, to form metallic containers having well known lock and lap side seams with non-metallic packing strips disposed so as to be bent or folded into the hooks interengaging to form the locked portion of the seams and to extend beyond said hooks and be included between the lapped portions of the seams. The provision of solderless side seams of any form, and particularly those including non-metallic strip inserts of the character just mentioned, present problems when the open ends of formed container bodies are flanged to prepare them for seaming operations incident to end closure applications subsequently to be effected because the flanging devices conventionally employed serve to spread and disrupt or distort the seams at the portions thereof extended beyond the interlocked side seam hooks, thereby rendering difficult and sometimes impossible efficient sealing of the containers. Another difficulty experienced in the flanging of container bodies having this form of side seam was that of so turning the flanges that the seams formed in the ultimate sealing of the containers, and which included the flanges, would grip the seam at the extremity of the seam hook portions and efficiently seal the seam at this danger point devoid of solder and interlock. The present invention seeks to provide a novel container body flanging mechanism which will remedy the conditions and avoid the difficulties referred to.

The co-pending patent application Serial Number 371,974, hereinbefore referred to, discloses the particular solderless side seam including the non-metallic packing strip insert as well as the mechanism for applying the strip, and in that application disclosure reference is made to a complete body maker or machine composed of three sections, namely, the section disclosed in that application and which includes the packing strip applying mechanism, the double blank ejecting devices, and suitable means for feeding the blanks and also for grain breaking the same after the usual custom, a second section comprising a standard form of body maker from the

position of the blank notching mechanism on through the forming station, and a third section comprising a flanging mechanism for flanging the ends of the formed container bodies immediately after they are formed. This third machine section constitutes the subject matter of the present invention.

An object of the invention is to provide a machine for flanging container bodies of the character stated and embodying a continuously rotated rotor having a plurality of can body receiving and end confining pockets therein, means for feeding formed containers one by one into said pockets, and reciprocable flanging heads movable simultaneously toward or from each other and effective to engage in container body ends confined in said pockets and flange said ends without improperly spreading or distorting the side seams at said ends.

Another object of the invention is to provide a machine of the character stated in which the container receiving and confining pockets are composed of inner, fixed half mold portions, and outer swingable half mold portions, and in which is included novel means for swinging the outer half mold portions to and from container body confining positions, and means for securely holding said half mold portions in the container body confining position while the flanging operation progresses.

Another object of the invention is to provide a machine of the character stated in which the container body feeding means includes a shelf-like pocket onto which container bodies are individually fed from the forming mechanism, and in which the outwardly swung outer half mold pocket portions successively engage and pick up can bodies from said shelf-like pocket and swing them into position against the inner, fixed half mold portions.

Another object of the invention is to provide a machine of the character stated in which the reciprocable flanging heads each have a notch for receiving end extremities of the interlocking hook portions of the side seams, thereby to flange the can body ends in close to and without interference by said end extremities, and in which the can body feeding means including the shelf-like pocket and the outer half mold pocket portions have provision for assuring alignment of the container body side seams with said flanging head notches.

Another object of the invention is to provide a machine of the character stated in which each swingable outer half mold portion has associated

therewith a swingable member effective to assist in controlling the movement of the container bodies into the fixed, inner half mold portions and for stripping the container bodies from said half mold portions after completion of the flanging function.

With the above and other objects in view which will more fully appear, the nature of the invention will be more clearly understood by following the description, the appended claims, and the several views illustrated in the accompanying drawings.

In the drawings:

Figure 1 is a side elevation illustrating a container body flanging machine embodying the invention, a fragment of a body maker also being shown.

Figure 2 is a left end elevation of the flanging machine illustrated in Figure 1, the horn along which the container bodies are fed to the machine being omitted and the container body receiving pocket mounting being illustrated in section.

Figure 3 is a central vertical longitudinal section of the flanging machine.

Figure 4 is a vertical cross section taken on the line 4-4 on Figure 3.

Figure 5 is a fragmentary sectional view taken substantially on the line 5-5 on Figure 2.

Figure 6 is a somewhat diagrammatic central vertical cross section illustrating various positions of the pocket forming half mold portions and the container stripper fingers, the superposed relation of the swingable half mold position determining cam and the finger position determining cam being illustrated in the dotted lines and the dot and dash lines respectively.

Figure 7 is a fragmentary longitudinal section through one of the flanging units, the flange heads being illustrated as moved to the flanging position.

Figure 8 is a fragmentary longitudinal sectional view illustrating one of the swingable half mold portions in pick up relation with the container supporting pocket.

Figure 9 is a fragmentary sectional view of the container supporting pocket taken substantially on the line 9-9 on Figure 8.

Figure 10 is an enlarged fragmentary sectional view illustrating the engagement of one of the aligning ribs of a swingable outer mold half portion with a container side seam portion engaging the seam.

Figure 11 is an enlarged fragmentary sectional view showing the side seam extremity receiving notch in one of the flanging heads.

Figure 12 is a fragmentary cross sectional view taken on the line 12-12 on Figure 11 and illustrating how a side seam extremity engages in a flanging head notch.

Figure 13 is a fragmentary edge view illustrating how the free ends of the swingable outer mold half portions interlock with the associated inner, fixed half mold portions.

Figure 14 is a longitudinal section through the horn along which container bodies are fed to the flanging machine container supporting pocket.

Figures 15 and 16 are detail vertical cross sections of the horn taken respectively on the lines 15-15 and 16-16 on Figure 14.

In the example of embodiment of the invention herein illustrated a fragment of the delivery end of a standard form of body maker is indicated at 5, and it is beneath the arch 6 of this unit that the container bodies to be flanged in

the flanging machine herein disclosed are finally shaped and have their interlocking seam hooks brought together and bumped in completion of the solderless side seam.

5 The flanging machine proper includes a base frame 7 having an end extension 8 at its front end, or the end toward which container bodies are fed, two spaced lateral extensions 9 at its right hand side, and a lateral extension 10 at its left side. See Figures 1, 2 and 4 of the drawings. Between the spaced extensions 9 the base frame includes a downwardly and outwardly inclined portion 11 which serves as a delivery chute for flanged container bodies and supports a plurality of spaced chute rails 12 and parallel spaced confining side walls 13.

10 At its rear end the machine includes a frame standard 14 having a gear housing portion 15 equipped with a removable cover plate 16. The irregular opening 17 in the front wall of the housing portion is closed by a plate cam 18 having an actuator groove 19 formed therein, and a hub portion 20 to which a grooved cam head 21 is 15 stationarily fixed as at 22. See Figure 3. The cam head 21 is equipped with an actuator groove 23, and the purpose of the cam grooves 19 and 23 will become apparent as this description of the invention progresses.

15 The fixed cam head 21 forms a bearing, as at 24, for one end of a main rotary shaft 25, the other end of the shaft having bearing, as at 26, in a bearing sleeve 27. See Figure 3. The bearing sleeve 27 has a plate cam 28 fixed thereon, as at 29, and is spline-mounted, as at 30, in a bearing standard 31 fixed upon the frame extension 8. The plate cam 28 is equipped with an actuator groove 32, and the sleeve 27 is secured, as at 33, to a cam head 34 which surrounds the shaft 25 and is equipped with an actuator groove 35. The purposes of the cam grooves 32 and 35 20 will later become apparent.

25 The sleeve 27 is externally threaded, as at 36, and is engaged by an internally threaded hand wheel 37 held captive by connection at 38 with the frame standard 31. Thus by rotating the hand wheel 37, the sleeve 27, the plate cam 28 and the cam 34 may be moved longitudinally on the shaft 25.

30 Intermediately of the cams 21 and 34 the shaft 25 carries two rotors 39 disposed in longitudinally spaced relation, as shown in Figure 3, and mounted for rotation with said shaft. These rotors are bridged over by a pair of bridge frame pieces 40 which are disposed in spaced parallel 35 relation and are mounted on the frame extensions 9 and 10 in the manner best illustrated in Figures 1 to 4 of the drawings.

35 A vertical standard portion 41 extends upwardly from the frame standard 14 and in this, the bridge piece 40, and the standard 31, a frame rod 42 is mounted. See Figures 1 to 4.

40 A large gear 43 is keyed on the shaft 25 within the housing portion 15 and is driven by an intermediate gear 44 also mounted within the housing portion 15, on a stud shaft 45, and which is 45 in turn driven by a small gear 46 fixed to rotate with a large gear 47 mounted on a stud shaft 48. The large gear 47, like the gears 46 and 44, is mounted in the housing portion 15, and it meshes 50 with and is driven by a driver gear 49 mounted in an extension 50 of the main gear housing and carried on an extension of the main drive shaft 51 of the body maker which feeds containers to be flanged into the improved flanging machine. 55 See Figures 2 and 5.

In practice, the horn about which the container bodies are formed, and against which the solderless lock and lap side seams thereof are bumped, is extended, as at 52, to a point at which can bodies are to be delivered for being flanged in the improved flanging machine. This extended free end of the horn is supported on a roller 53 carried on a horizontal arm of a bell crank lever 54, said roller being capable of a limited amount of downward movement to permit passage of container bodies under the control of movement limiting screws 55 and 56, said roller being constantly urged against the horn by a tension spring 57.

The horn extension 52 is grooved along its under surface, as at 58, and has a rail 59 secured in said groove, as at 60. The rail is grooved, as at 61, to receive the inwardly directed side seam extension formed by the interlocking hooks of the side seam, thereby to definitely retain a given position of the container bodies as they are fed along the horn. The horn extension includes the usual slide rails or spacers 62 and a reciprocable feed bar 63 having yieldably projecting feed fingers 64 effective to intermittently feed container bodies successive, definite distances along the horn. If desired, additional keeper detents 65 may be provided for intercepting containers fed the successive steps by the finger bar 63 and overcome any tendency of the container bodies to move back with the finger bar during its movements of retraction.

As each container body is fed off the end of the horn extension it is received in a half cylindrical rest pocket 66 having a bracket extension 67 which is secured, as at 68, on the machine framing. The stationary rest pocket 66 includes an abutment wall portion 69 which confines containers against endwise displacement and which is spaced, as at 70, from the main body of the pocket a distance sufficient to permit passage of movable, container engaging half mold portions at either side of and closely adjacent to the end extremities of the rest pocket 66 in the manner best illustrated in Figure 8 of the drawings. It will be observed that the main body portion of the rest pocket 66 is of a length for permitting the end extremities of containers 71 to project beyond the ends of the pocket in the manner indicated at 72. The rest pocket 66 is provided with an aligning rib 73 which is engageable in the groove 74 disposed at one side of the interlocked seam hooks 75 in the manner best illustrated in Figure 9 of the drawings. The groove 74 is formed in a well known manner during the bumping of the side seam and results from the provision of a seam locking rib effective to prevent disruption of the interlocked relation of the hooks of the solderless side seams 75 as a result of stresses set up in shipment or handling of the finished containers. By engagement of the aligning rib 73 in the seam groove 74 as the container bodies are individually delivered into the rest pocket 66, the alignment of the side seams attained by engagement of the seams with the horn groove 61, is effectively maintained. The solderless side seam 75 preferably, but not necessarily, includes a packing insert 76 of paper or other non-metallic material.

Each rotor 39 includes a sleeve surrounding the shaft 25 from which webs 71 extend and carry four sets of axially aligned cylindrical bearings 78. See Figures 1, 3 and 7 of the drawings. Each bearing 78 supports a longitudinally reciprocable plunger or piston 79 which has a non-

circular portion 80 within the bearing and engaged by a removably mounted key-piece 81 effective to prevent rotation of the plunger within the bearing. The plungers 79 of each opposed set extend from the inner ends of the bearings 78 and are equipped with heads 82 to each of which a flanging head 83 is secured, as at 84, against a spacer shim ring 85 of selected length. At its outer end, each plunger 79 carries a roll 10 86 engageable in the adjacent cam groove 23 or 35, and the cam grooves are effective to cause the plunger of each set to move inwardly toward each other or outwardly away from each other during the cycle of operation of the machine 15 designed to effect a proper flanging of the can bodies.

Each bearing 78 at the end of the machine at which the plate cam 18 is mounted is equipped with two spaced bearing sleeve extensions 87 in 20 which a shaft 88 is rockably mounted. See Figure 7. Each such shaft has a crank 89 affixed thereto which is equipped with a roller 90 engageable in the actuator groove 19 of the adjacent cam 18, and is held against longitudinal movement in the bearing extensions 87 by said crank and a stop collar 91 fixed thereon. Each shaft 88 has two half circular, outer half mold members 92 secured thereon, as at 93, in the spaced relation illustrated in Figure 7. The outer half mold members 92 are movable by the cam and crank connections 19, 89 into and out of cooperative relation with inner half mold recesses 94 formed in disks 95 secured in parallel spaced relation on the rotors 39. When the outer and inner half mold equipments 92 and 94 are moved into cooperative relation, as indicated at the right in Figure 4 of the drawings, they form complete molding circles for opposing the ends of containers while they are being flanged. In order to assure against disrupting of this perfect molding cooperation of the molding equipments 92 and 94, the free ends of the members 92 interlock at 96 with the disks 95 in the manner best illustrated in Figures 4, 6 and 13 of the drawings.

Between each pair of outer half mold members 92, two sleeves 97 rockably surround the shaft 88, said sleeves being disposed in end abutment and removably interlocked, as at 98. See Figures 7 and 8 of the drawings. Each sleeve 97 carries a container confining and stripping finger 99 and each of the outer half mold members 92 is recessed, as at 100, to partially clear the adjacent stripper finger and permit each stripper finger and outer half mold member 99 and 92 to pass at one end or the other of said rest pocket 66 in the manner illustrated in Figure 8. Each shaft 88 includes an axial bore 101 in the inner end thereof for receiving the inner end of a rock shaft 102 which is secured in driving relation with one of the sleeves 97 through the medium of a screw 103 extending through a longitudinal slot 104 in the surrounding portion of the shaft 88, thereby to permit a degree of relative movement of the shaft portions 88 and 102 about the common axis.

Each shaft 102 is splined, as at 105, in a sleeve 106 rockably mounted in a bearing extension 107 from the respective plunger bearing 78 disposed at that end of the machine at which the plate cam 28 is mounted. Each sleeve 106 has a crank 108 keyed thereto, said crank being equipped with a roller 109 engaging in the actuator groove 32 of the adjacent plate cam 28. The sleeves 106 are held against longitudinal movement in the bearing extensions 107 by the cranks 108 and stop collars 110 secured on said sleeves.

In order to securely hold the outer half mold members 92 against the inner half mold equipments 94 during flanging operations, each of the outer half mold members 92 carries a roller 111 which is engageable with a holdown track 112. The holdown tracks are mounted on the frame rod 42 and on another frame rod 113 disposed at the side of the machine and which passes through the bridge pieces 40. See Figures 3, 4 and 6. The holdown tracks start at the rod 42 and terminate at 114 just beneath the rod 113.

A solderless side seam equipped container, such as are to be flanged in the improved machine herein disclosed, is described in detail in the U. S. Letters Patent 2,171,711, issued to Plumb, et al., Sept. 5, 1939. In this form of container the lapped portions of the side seam are not as long as in standard forms of lock and lap seam equipped containers, and these entire lapped portions are rolled into the side seam so as to bind the lapped portions against the included packing strip and against the end extremities of the locked portions of the side seam thereby to assure against leakage at the ends of the side seams. The flanging of container bodies thus formed heretofore presented problems because it was impossible to project flanging heads a proper distance into the container ends because of engagement with the extremities of the locked portion of the seams, nor was it possible to effect the flanging operation without improperly spreading and disrupting the container body seams at the lapped portions. These problems have been avoided in the present machine by provision of the peculiar arrangement of half mold, can end supporting portions, and by providing each flanging head 83 with a notch 115 in which to receive an extremity of the interlocked side seam portion of a container being flanged. By reason of the provision of the guiding groove 61 along the bottom of the horn extension 52, the seam position retaining rib 73 on the rest pocket 66, and the provision of seam position retaining ribs 116 on the outer half mold portions 92, proper alignment of the end extremities of each container body side seam with the notches 115 in the flanger heads 83 adapted to engage in and effect the flanging of the ends of that particular container is assured.

When the machine is in operation, continuous rotation is imparted to the rotor comprised by the shaft 25, the rotor parts 39 and the plungers 79 reciprocable in the bearings thereof, and the inner and outer half mold members, through the medium of the transmission gearing best illustrated in Figures 2 and 5 of the drawings, the power being applied from the main shaft extension 51 from the body maker. As the rotor rotates relatively to the stationary cams 21, 34, 18 and 23, the plungers 79 are reciprocated in the bearings 78 so as to alternately move toward and from each other, and the outer half molds are alternately swung away from their cooperative relation with the inner half molds, as indicated at the central lower and left portions of Figure 4, and then again to the cooperative relation with said inner mold portions as indicated at the right in said Figure 4. The cam grooves 23 and 19, and 35 and 32 are so co-related that the flanging heads are moved into engagement with the half mold sections while they are in the container end embracing and confining cooperative relation illustrated at the right in Figure 4 for the purpose of flanging the short length of can body projecting at each end beyond said half mold members.

The container bodies fed step by step along the horn extension 52 by the feed bar 63 are delivered one by one onto the rest pocket 66 in the manner illustrated in Figures 6 and 8 of the drawings. Each container body thus placed on the rest pocket is picked up by the next advancing, outwardly swung outer half mold in the manner illustrated at the left in Figure 6 of the drawings, and it will be observed that at the time each 10 container is picked up the fingers 99 overlie the same sufficiently to prevent displacement of the container body from the outer half mold. As the rotor continues its upward movement, like portions of the cam grooves 19 and 32 will cause 15 the outer half molds 92 and the fingers 99 to move together, the outer half molds 92 serving to move the container body into the cooperating inner mold recesses 94 and the fingers 99 serving to control this movement of the container body and prevent said container body moving freely away from the outer half mold members 92. As the unit reaches the top of its path of 20 travel, as viewed in Figure 6, the rollers 111 of the unit will engage the holdown tracks 112 and secure the cooperative relation of the inner and 25 outer half mold equipments, the interengaging notches 96 also serving to lock the free ends of the members 92 against displacement in the direction of the axis of the rotor. While the half 30 mold members are thus held securely about the end portions of the container body the cam grooves 23 and 35 force the plungers 79 toward each other and the flanging heads engage in and 35 flange the ends of the container body. After the container body has been thus flanged, the 40 rollers 111 roll off the ends 114 of the holdown tracks 112 and free the half molds to swing to the container discharging position illustrated at the bottom in Figure 6. The cam tracks 19 and 45 32 are so shaped that the fingers 99 follow the movement of the outer half molds 92 to the container body discharging position so as to act as stripper members in the manner illustrated in Figure 6, but it will be observed by reference to 50 this figure that the cam track permits the half mold members 92 to open before the cam track 32 causes the fingers 99 to start their outward or container stripping movement, and obviously movement of the half mold members 92 away 55 from the cooperating half mold recesses 94 does not start until the respective rollers 111 leave contact with the discharge end 114 of the holdown tracks 112.

While passing from the flanged container body 60 discharging position illustrated at the bottom of Figure 6, each outer half mold member is retained in the extended position illustrated until it reaches the container pick up position illustrated at the left in said Figure 6. While moving 65 to the pick up position the position controlling cam groove moves the associated finger equipment 99 inwardly with respect to the half mold members 92 so as to clear a container resting on the rest pocket 66, and then again to the position 70 illustrated at the left in Figure 6 to overlie the container body after it is picked up by the half mold 92 and prevent displacement of the container body therefrom. While passing from the position illustrated at the left in Figure 6, the half mold members 92 are moved into cooperative relation with the inner mold recesses 94, and after the complete embracement and confinement 75 of the container body to be flanged is thus completed, the roller 111 passes under the holdown

track 112 to secure the cooperative relation of the inner and outer half mold members.

By reason of the provision of the notches 115 in the flanging heads 83, the container end flanges can be formed very close to the end extremity of the interlocked side seam portions thereby making it possible to turn the flanged portions into the seam structure by which end closures are ultimately applied to the container bodies and assure against leakages at the ends of the seams despite the fact that said seams are not secured by soldering. As previously described, the engagement of the side seam extremities in the flanging head notches 115 is assured by maintaining constant control of the positioning of the side seams by engagement thereof with the groove 61 along the bottom of the horn extension, the aligning rib 73 on the rest pocket 66, and the aligning ribs 116 on the outer half mold members 92 which line up with said flanging head notches.

As previously stated, shim rings 85 of different lengths can be interposed between the plungers 79 and the flanging heads 83, thereby to vary the spaced relation of said heads and adapt the machine for flanging operations on containers of varied length. Also, by turning the hand wheel 37, the cams 28 and 34 can be moved longitudinally on the shaft 25 as an additional means of varying the spaced relation of the flanging heads. It is to be assumed, of course, that the rotor portion adjacent the cam 34 also will be moved longitudinally on the shaft 25 with which it rotates and that the spaced relation of the hold-down tracks 112 will be suitably altered by adjustment thereof along the rod 42.

It is of course to be understood that the details of structure and arrangement of parts may be variously changed and modified without departing from the spirit and scope of my invention.

I claim:

1. In a machine for flanging the ends of container bodies round in cross section having lock and lap side seams, means for embracing and closely confining a container body just short of an end thereof to be flanged thereby to leave extended only a short length of said end, means for feeding container bodies endwise to and positioning them in said embracing and confining means always with the side seams thereof disposed in a predetermined position, a flanging head having a portion shaped to snugly fit said end and merging into an enlarged end flanging portion, means for forcing the head into and against the container body end to flange the same, said snug fitting head portion having a notch therein to receive the end extremity of the lock portion of the container body side seam at said end, and means on said embracing and confining means presented for engagement by container body side seam portions as the container bodies move endwise into engagement with said embracing and confining means effective for definitely placing said side seams relatively to said notches.

2. In a machine for flanging the ends of container bodies round in cross section having lock and lap side seams, means for embracing and closely confining a container body just short of each end thereof thereby to leave extended only a short length of each said end, reciprocable flanging heads engageable with the ends of the container body and each having a portion shaped to snugly fit a container body end and merging into an enlarged end flanging portion, means for

reciprocating said heads simultaneously toward and from each other for first forcing the heads into and against said container body ends to flange the same and for then retracting said heads, each said snug fitting head portion having a notch therein for receiving the end extremity of the lock portion of the container body at that particular end of the container body, means for feeding container bodies endwise to said embracing and confining means, means engageable with side seam portions of the container bodies while they are being fed endwise toward said embracing and confining means and effective to always definitely and properly place the container body side seams relatively to said notches, and means on said embracing and confining means presented for engagement by container body side seam portions as the container bodies move endwise into engagement with said embracing and confining means effective for maintaining said definite and proper placement of said side seams relatively to said notches.

3. In a machine for flanging the ends of container bodies, a rotor having a plurality of half-cylindrical inner half molds and a complementary plurality of half-cylindrical outer half molds swingably mounted thereon and swingable into cooperative relation with said inner half molds for embracing and closely confining container bodies just short of an end thereof thereby to leave extended only a short length of said end or out of such cooperative relation to permit introduction of container bodies into position for embracement and confinement or discharge thereof from such embracement and confinement, bearing members rotatable with the rotor and individually aligned with the half molds when they are in cooperative relation, flanging heads reciprocably mounted in said bearing members and movable into engagement with container body ends when they are embraced and confined in said molds, stationary cam means for imparting reciprocation to said flanging heads, and means including crank arms and stationary cams engaged by said arms during rotation of the rotor for positively swinging the outer half molds from and again into cooperative relation with the inner half molds between successive flanging functions of said flanging heads.

4. In a machine for flanging the ends of container bodies, a rotor having a plurality of half-cylindrical inner half molds and a complementary plurality of half-cylindrical outer half molds swingably mounted thereon and swingable into cooperative relation with said inner half molds for embracing and closely confining container bodies just short of an end thereof thereby to leave extended only a short length of said end or out of such cooperative relation to permit introduction of container bodies into position for embracement and confinement or discharge thereof from such embracement and confinement, bearing members rotatable with the rotor and individually aligned with the half molds when they are in cooperative relation, flanging heads reciprocably mounted in said bearing members and movable into engagement with container body ends when they are embraced and confined in said molds, stationary cam means for imparting reciprocation to said flanging heads, hold-down track means for securely holding the outer half molds in cooperative relation with the inner half molds during flanging functions of the flanging heads, and means including stationary cams for swinging the outer half molds from and

again into cooperative relation with the inner half molds between successive flanging functions of said flanging heads.

5. In a machine for flanging the ends of container bodies, a rotor having a plurality of half-cylindrical inner half molds and a complementary plurality of half-cylindrical outer half molds swingably mounted thereon and swingable into cooperative relation with said inner half molds for embracing and closely confining container bodies just short of an end thereof thereby to leave extended only a short length of said end or out of such cooperative relation to permit introduction of container bodies into position for embracement and confinement or discharge thereof from such embracement and confinement, flanging heads forcible into the container body ends while they are embraced and confined for flanging the short end extensions of said container bodies, a stationary container body rest pocket for supporting individual container bodies in position for being picked up by outwardly swung outer half molds and swung thereby into the associated inner half molds, and means for individually feeding container bodies to said rest pocket.

6. In a machine for flanging the ends of container bodies, a rotor having a plurality of half-cylindrical inner half molds and a complementary plurality of half-cylindrical outer half molds swingably mounted thereon and swingable into cooperative relation with said inner half molds for embracing and closely confining container bodies just short of an end thereof thereby to leave extended only a short length of said end or out of such cooperative relation to permit introduction of container bodies into position for embracement and confinement or discharge thereof from such embracement and confinement, flanging heads forcible into the container body ends while they are embraced and confined for flanging the short end extensions of said container bodies, a stationary container body rest pocket for supporting individual container bodies in position for being picked up by outwardly swung outer half molds and swung thereby into the associated inner half molds, and finger means swingable in cooperation with each outer half mold and effective to control movement of container bodies into the inner half molds and for stripping and discharging flanged container bodies from said inner half molds.

7. In a machine for flanging the ends of container bodies, a rotor having a plurality of half-cylindrical inner half molds and a complementary plurality of half-cylindrical outer half molds swingably mounted thereon and swingable into cooperative relation with said inner half molds for embracing and closely confining container bodies just short of an end thereof thereby to leave extended only a short length of said end or out of such cooperative relation to permit introduction of container bodies into position for embracement and confinement or discharge thereof from such embracement and confinement, bearing members rotatable with the rotor and individually aligned with the half molds when they are in cooperative relation, flanging heads reciprocably mounted in said bearing members and movable into engagement with container body ends when they are embraced and confined in said molds, stationary cam means for imparting reciprocation to said flanging heads, means including stationary cams for swinging the outer half molds from and again into co-

operative relation with the inner half molds between successive flanging functions of said flanging heads, a stationary container body rest pocket for supporting individual container bodies in position for being picked up by outwardly swung outer half molds and swung thereby into the associated inner half molds, and means for individually feeding container bodies to said rest pocket.

10 8. In a machine for flanging the ends of container bodies, a rotor having a plurality of half-cylindrical inner half molds and a complementary plurality of half-cylindrical outer half molds swingably mounted thereon and swingable into cooperative relation with said inner half molds for embracing and closely confining container bodies just short of an end thereof thereby to leave extended only a short length of said end or out of such cooperative relation to permit introduction of container bodies into position for embracement and confinement or discharge thereof from such embracement and confinement, bearing members rotatable with the rotor and individually aligned with the half molds when they are in cooperative relation, flanging heads reciprocably mounted in said bearing members and movable into engagement with container body ends when they are embraced and confined in said molds, stationary cam means for imparting reciprocation to said flanging heads, means including stationary cams for swinging the outer half molds from and again into cooperative relation with the inner half molds between successive flanging functions of said flanging heads, a stationary

15 20 25 30 35 40 45 50 55 60 65 70 75

container body rest pocket for supporting individual container bodies in position for being picked up by outwardly swung outer half molds and swung thereby into the associated inner half molds, and means for individually feeding container bodies to said rest pocket, each said flanging head having a notch therein for receiving an end extremity of the lock portion of a container body side seam, and said feeding means said rest pocket and said outer half molds including seam engaging means effective to assure alignment of can body side seams with said flanging head notches.

10. In a machine for flanging the ends of container bodies, a rotor having two spaced disk portions equipped with a plurality of sets of aligned half-cylindrical peripheral recesses forming inner container body half molds and a complementary plurality of sets of half-cylindrical outer half molds swingably mounted thereon and swingable into cooperative relation with said inner half molds for embracing and closely confining container bodies just short of each end thereof thereby to leave extended only a short length of each end of said container body or out of such cooperative relation to permit introduction of container bodies into position for embracement and confinement or discharge thereof from such embracement and confinement, flanging heads forcible into the ends of the container bodies while they are embraced and confined, means for moving said outer half molds and flanging heads in timed relation, and means for supporting individual container bodies in position for being picked up on the outer half molds while they are swung away from the inner half molds.

11. In a machine for flanging the ends of container bodies, a rotor having two spaced disk portions equipped with a plurality of sets of aligned half-cylindrical peripheral recesses forming inner container body half molds and a complementary plurality of sets of half-cylindrical outer half molds swingably mounted thereon and swingable into cooperative relation with said inner half molds for embracing and closely confining container bodies just short of each end thereof thereby to leave extended only a short length of each end of said container body or out of such cooperative relation to permit introduction of container bodies into position for embracement and confinement or discharge thereof from such embracement and confinement, flanging heads forcible into the ends of the container bodies while they are embraced and confined, means for moving said outer half molds and flanging heads in timed relation, means for supporting individual container bodies in position for being picked up on the outer half molds while they are swung away from the inner half molds, and finger means swingable in cooperation with each set of outer half molds and effective to control movement of container bodies into the inner half molds on said swingable outer half molds and for stripping and discharging flanged container bodies from said inner half molds, each said flanging head having a notch therein for receiving an end extremity of the lock portion of a container body side seam, and said feeding means said rest pocket and said outer half molds including seam engaging means effective to assure alignment of can body side seams with said flanging head notches.

12. In a machine for flanging the ends of container bodies having lock and lap side seams, a rotor having two spaced disk portions equipped with a plurality of sets of aligned half-cylindrical peripheral recesses forming inner container body half molds and a complementary plurality of sets of half-cylindrical outer half molds swingably mounted thereon and swingable into cooperative relation with said inner half molds for

embracing and closely confining container bodies just short of each end thereof thereby to leave extended only a short length of each end of said container body or out of such cooperative relation to permit introduction of container bodies into position for embracement and confinement or discharge thereof from such embracement and confinement, flanging heads forcible into the ends of the container bodies while they are embraced and confined, means for moving said outer half molds and flanging heads in timed relation, a stationary rest pocket for supporting individual container bodies in position for being picked up on the outer half molds while they are swung away from the inner half molds, means for individually feeding container bodies to said rest pocket, each said flanging head having a notch therein for receiving an end extremity of the lock portion of a container body side seam, and said feeding means said rest pocket and said outer half molds including seam engaging means effective to assure alignment of can body side seams with said flanging head notches.

13. In a machine for flanging the ends of container bodies having lock and lap side seams, a rotor having two spaced disk portions equipped with a plurality of sets of aligned half-cylindrical peripheral recesses forming inner container body half molds and a complementary plurality of sets of half-cylindrical outer half molds swingably mounted thereon and swingable into cooperative relation with said inner half molds for embracing and closely confining container bodies just short of each end thereof thereby to leave extended only a short length of each end of said container body or out of such cooperative relation to permit introduction of container bodies into position for embracement and confinement or discharge thereof from such embracement and confinement, flanging heads forcible into the ends of the container bodies while they are embraced and confined, means for moving said outer half molds and flanging heads in timed relation, a stationary rest pocket for supporting individual container bodies in position for being picked up on the outer half molds while they are swung away from the inner half molds, means for individually feeding container bodies to said rest pocket, holddown track means for securely holding the outer half molds in cooperative relation with the inner half molds during flanging functions of the flanging heads, and finger means swingable in cooperation with each set of outer half molds and effective to control movement of container bodies into the inner half molds on said swingable outer half molds and for stripping and discharging flanged container bodies from said inner half molds, each said flanging head having a notch therein for receiving an end extremity of the lock portion of a container body side seam, and said feeding means said rest pocket and said outer half molds including seam engaging means effective to assure alignment of can body side seams with said flanging head notches.

14. In a machine for flanging the ends of container bodies having lock and lap side seams, means for embracing and closely confining a container body just short of each end thereof thereby to leave extended only a short length of each said end, reciprocable plungers, flanging heads removably and replaceably mounted on said plungers and engageable with the ends of the container body and each having a portion shaped to snugly fit a container body end and merging

into an enlarged end flanging portion, means for reciprocating said plungers and heads simultaneously toward and from each other for first forcing the heads into and against said container body ends to flange the same and for then retracting said heads, each said snug fitting head portion having a notch therein for receiving the end extremity of the lock portion of the container body at that particular end of the container body, and means including selective length shim rings disposed directly between said heads and plungers for adjustably determining the spaced relation of said flanging heads to permit flanging of container bodies of varied lengths.

15. In a machine for flanging the ends of container bodies, a rotor having two spaced disk portions equipped with a plurality of sets of aligned half-cylindrical peripheral recesses forming inner container body half molds and a complementary plurality of sets of half-cylindrical outer half molds swingably mounted thereon and swingable into cooperative relation with said inner half molds for embracing and closely confining container bodies just short of each end thereof thereby to leave extended only a short length of each end of said container body or out of such cooperative relation to permit introduction of container bodies into position for embracement and confinement or discharge thereof from such embracement and confinement, flanging heads forcible into the ends of the container bodies while they are embraced and confined, means for moving said outer half molds and flanging heads in timed relation, means for supporting individual container bodies in position for being picked up on the outer half molds while they are swung away from the inner half molds, and means for adjusting the spaced relation of the disk portions to position the complementary half molds for receiving container bodies of varied lengths.

16. In a machine for flanging the ends of container bodies having lock and lap side seams, a rotor having two spaced disk portions equipped with a plurality of sets of aligned half-cylindri-

cal peripheral recesses forming inner container body half molds and complementary plurality of sets of half-cylindrical outer half molds swingably mounted thereon and swingable into cooperative relation with said inner half molds for embracing and closely confining container bodies just short of each end thereof thereby to leave extended only a short length of each end of said container body or out of such cooperative relation to permit introduction of container bodies into position for embracement and confinement or discharge thereof from such embracement and confinement, flanging heads forcible into the ends of the container bodies while they are embraced and confined, means for moving said outer half molds and flanging heads in timed relation, a stationary rest pocket for supporting individual container bodies in position for being picked up on the outer half molds while they are swung away from the inner half molds, means for individually feeding container bodies to said rest pocket, holdown track means for securely holding the outer half molds in cooperative relation with the inner half molds during flanging functions of the flanging heads, and finger means swingable in cooperation with each set of outer half molds and effective to control movement of container bodies into the inner half molds on said swingable outer half molds and for stripping and discharging flanged container bodies from said inner half molds, each said flanging head having a notch therein for receiving an end extremity of the lock portion of a container body side seam, said feeding means said rest pocket and said outer half molds including seam engaging means effective to assure alignment of can body side seams with said flanging head notches, means for adjusting the spaced relation of the disk portions to position the complementary half molds for receiving container bodies of varied lengths, and means including adjustable length shim rings for adjusting the spaced relation of said flanging heads for proper engagement with container bodies of varied lengths.

PAUL E. PEARSON.
